UNITED STATES PATENT OFFICE.

CHARLES LOUIS FAIVRE, OF LE LOCLE, SWITZERLAND.

ALARM CLOCK AND WATCH.

1,011,596.

Specification of Letters Patent.

Patented Dec. 12, 1911.

Application filed September 30, 1905, Serial No. 280,808. Renewed February 13, 1911. Serial No. 608,396.

To all whom it may concern:

Be it known that I, CHARLES LOUIS FAIVRE, watch - manufacturer, citizen of Switzerland, residing at Le Locle, Canton of Neuchatel, Switzerland, have invented 5 new and useful Improvements in Alarm Clocks and Watches, of which the following is a specification.

This invention relates to alarm mechanism for application to clocks or watches 10 and consists in certain devices for locking and releasing the usual vibratory hammer and also manually operable means for effecting the release of the hammer, to operate 15 the alarm, at a predetermined time.

The invention will be more fully described in connection with the accompanying drawing and will be more particularly pointed out and ascertained in and by the 20 appended claims.

In the drawing:—Figure 1 is a view of the manually operable means for setting the alarm. Fig. 2, is a reverse view. Fig. 3, is an enlarged sectional view on line A—B 25 of Fig. 2. Fig. 4, is a sectional view on line C—D of Fig. 3.

Like characters of reference designate similar parts throughout the different figures of the drawing.

As shown in the drawing:—A portion of the time train is indicated in Fig. 2 by 30 wheels 1, 2, 3, 4 and 5, said wheel 5 meshing with a barrel pinion 6 actuated by a spring 7. Wheel 1, Figs. 1 and 3, is fast to the arbor of the hour hand, (not shown), and meshes with and is positively driven by 35 wheel o , of equal diameter, which is mounted on arbor k' . A wheel k , equal in diameter to wheel o , is also mounted on arbor k' 40 and is held thereby in frictional contact with wheel o to afford relative adjustment of the former with respect to the latter.

An improved adjusting or setting means is 45 provided for adjusting the setting wheel k which consists of the following construction. A swinging or adjusting member s , preferably in the form of the bell crank lever, is pivotally mounted at t to the pillar plate b or other stationary part and carries 50 at r a wheel p adapted to mesh with the setting wheel k and a wheel q , adapted to rotate with the wheel p and in mesh with a manually operable wheel v rotatably mounted at t . Said member s is provided with an 55 extension u adapted to normally project through the case, diagrammatically indi-

cated by line z . As will be seen by reference to Fig. 1, the manually operable wheel v also projecting beyond the case. A spring x engages the swinging member s and serves to normally hold the wheel p out of mesh with wheel k . An index k^2 secured to the wheel k rotates abreast of a graduated portion k^3 visible to the operator, so as to indicate the position to which the wheel k has 60 been set. 65

When it is desired to set the alarm mechanism the operator presses inwardly on the extension u against the action spring x while forcing the wheel p into mesh with the wheel k . Wheel k is then set by rotating the manually operable wheel v . A striker or hammer i is pivotally mounted at i' in a bridge i^2 and in the pillar plate b and is operated from a spring barrel i^3 through the 70 medium of wheels, i^4 , i^5 , i^6 and a ratchet wheel i^3 and escapement pawl i^8 which latter are mounted at i' . A gong n is secured to the pillar plate b by the mounting n' in striking proximity to the hammer i . Said 75 hammer i is provided with a projection h , Fig. 4, adapted to be engaged by a pin f provided with a knife edge f' and held thereby in a retracted position. The pin f is mounted in one end of the lever e which is secured 80 at its opposite end to a spindle or arbor c . A bridge a mounted on pillar plate b supports the lever e and forms a bearing for the arbor c . Said arbor c extends through the pillar plate b and carries on its opposite 85 end a hand or index d . Said index d extends from the arbor c toward the wheel k and into the plane of travel of a lug m mounted on said wheel. The disposition of the parts just described is such that when the lug m 90 engages the index d the latter serves through the arbor c and lever e to throw the pin f out of engagement with the projection h releasing the hammer i and permitting the same to operate under the action of the independently driven alarm train hereinbefore 95 described.

When the striker i is engaged by the pin f and held in a retracted position it is desirable to provide means serving to hold the 100 pin f in engagement with the shoulder h and it is necessary that said means permit of disengagement of the pin f from the projection h when the lug m engages the index d and to this end said means is designed to 105 yieldingly engage the lever e or other suitable part connected with the pin f . As 110

shown a spring is provided having forked arms g which engage the lever e at opposite sides. Said arms g terminate in a base g' rigidly secured to the bridge a . In assembling the parts the base g' is mounted upon the bridge a in a manner to cause the arms g to normally hold the pin f in engaging proximity to the projection h as clearly shown in Fig. 2.

10 I claim:—

1. A device of the class described comprising in combination a gong, a striker therefor, a pivotally mounted lever for holding said striker in a retracted position, a spring yoke engaging said lever on opposite sides to hold it in locking relation with said striker, and a frictionally acting gear train for displacing said lever.

2. A device of the class described comprising in combination a gong, a striker therefor, a pivotally mounted lever for holding said striker in a retracted position, a spring yoke engaging said lever on opposite sides to hold it in locking relation with said striker, a positively driven pinion, and an adjustable pinion frictionally driven by said first-mentioned pinion and coöperating with said lever to release said striker.

3. A device of the class described comprising in combination a gong, a striker therefor having a lug h provided with a knife edge, a pivotally mounted lever provided with a pin f having a knife edge engaging said lug, a spring yoke engaging said lever on opposite sides to hold it in locking relation with the striker, a spindle for said lever, a hand or pointer for said spindle, an adjustable pinion provided with a lug adapted to engage said hand, and a positively driven pinion frictionally driving said adjustable pinion.

4. A device of the class described comprising in combination a gong, a striker therefor, a pivotally mounted lever for holding said striker in a retracted position, a spring yoke engaging said lever on opposite sides to hold it in locking relation with said striker, a frictionally acting gear train for displacing said lever, and setting mechanism for said frictionally acting gear train.

5. A device of the class described comprising in combination a gong, a striker therefor, a pivotally mounted lever for holding said striker in a retracted position, a spring yoke engaging said lever on opposite sides to hold it in locking relation with said

striker, a positively driven pinion, and an adjustable pinion frictionally driven by said first-mentioned pinion and coöperating with said lever to release said striker, and setting mechanism for said adjustable pinion.

6. A device of the class described comprising in combination a gong, a striker therefor, a pivotally mounted lever provided with a pin having a knife edge for holding said striker in a retracted position, a spring yoke engaging said lever on opposite sides to hold said pin in locking relation with said striker, an index or hand associated with said lever, a positively driven pinion, an adjustable pinion frictionally driven by first mentioned pinion and provided with a lug adapted to engage said index, setting mechanism for actuating said adjustable pinion and comprising a swinging lever provided with an extension adapted to project through the case, a wheel for said lever adapted to mesh with said adjustable pinion, a second wheel rotating with said first wheel, a third wheel meshed with said second wheel adapted to project through the watch case, and a spring engaging said lever and normally holding it in an inoperative position.

7. A device of the class described comprising in combination, a gong, a striker therefor, means for holding said striker in a retracted position, oppositely acting yielding elements engaging said means to hold the same in locking relation with the striker, and mechanism for displacing said means.

8. A device of the class described comprising in combination, a time train, an actuating member driven thereby, an alarm train, a sounding element, a striking device operating thereon and driven from said alarm train, a movable member holding said striking device in a non-operating position, oppositely acting yielding elements engaging said movable member to hold the same in locking relation to the striker, and means associated with said movable member and normally out of engagement with said actuating member and adapted to be actuated thereby to release said striking device.

In testimony whereof I have signed my name to this specification in the presence of two subscribing witnesses.

CHARLES LOUIS FAIVRE.
